TYPEWRITER

James J. Bienkowski, Cazenovia, and Paul D. Younge,
Horseheads, N.Y., assignors to SCM Corporation, New York, N.Y.

Filed Jan. 2, 1973, Ser. No. 320,385

Term of patent 14 years

Int. Cl. D18—01

U.S. Cl. D64—11 A

FIG 1

FIG. 1 is a front perspective view of a typewriter showing our new design;

FIG. 2 is a top plan view;

FIG. 3 is a front elevational view;

FIG. 4 is a right side elevational view;

FIG. 5 is a rear elevational view; and

FIG. 6 is a left side elevational view.

The typebar guide and typebars are conventional and have been omitted for ease of illustration.

We claim:

The ornamental design for a typewriter, as shown and described.
